UNITED STATES PATENT OFFICE.

ADOLPH C. RECKER, OF OAKVILLE, CONNECTICUT, ASSIGNOR TO THE CHASE COMPANIES, INC., OF WATERBURY, CONNECTICUT, A CORPORATION.

DESIGN FOR A PLURAL LAMP-SOCKET.

57,930.

Specification for Design.

Patented May 17, 1921.

Application filed November 26, 1920. Serial No. 426,659. Term of patent 14 years.

To all whom it may concern:

Be it known that I, ADOLPH C. RECKER, a citizen of the United States, residing at Oakville, in the county of Litchfield and State of Connecticut, have invented a new, original, and ornamental Design for a Plural Lamp-Socket, of which the following is a specification, reference being had to the accompanying drawing, forming part thereof.

The figure is a side view of a plural lamp socket showing my new design.

I claim:

The ornamental design for a plural lamp socket as shown.

ADOLPH C. RECKER.
